US00D690588S

(12) **United States Design Patent**
Pipes et al.

(10) **Patent No.:** **US D690,588 S**
(45) **Date of Patent:** ** *Oct. 1, 2013

(54) **CONTAINER**

(75) Inventors: **Jerry Wayne Pipes**, Clemmons, NC (US); **Pankaj Patel**, Clemmons, NC (US); **Melissa Ann Clark**, Mocksville, NC (US); **Laya Katina Palmer Horton**, Winston-Salem, NC (US); **William Travis Lintner**, Winston-Salem, NC (US)

(73) Assignee: **R.J. Reynolds Tobacco Company**, Winston-Salem, NC (US)

(*) Notice: This patent is subject to a terminal disclaimer.

(**) Term: **14 Years**

(21) Appl. No.: **29/408,136**

(22) Filed: **Dec. 7, 2011**

(51) **LOC (9) Cl. 09-03**

(52) **U.S. Cl.**

USPC **D9/424**

(57) **CLAIM**

The ornamental design for a container, as shown and described.

DESCRIPTION

FIG. 1 is a top perspective view of a container showing the new design;

FIG. 2 is a left side view thereof;

FIG. 3 is an end view thereof;

FIG. 4 is a top perspective view of a further container showing the new design;

FIG. 5 is a left side view thereof; and,

FIG. 6 is an end view thereof.

The opposing end view not illustrated herein forms no part of the claimed design.

The broken line showing of a container represents unclaimed subject matter and forms no part of the claimed design.

1 Claim, 6 Drawing Sheets
